Attorney

UNITED STATES PATENT OFFICE.

GEORGE DONGES, OF PHILADELPHIA, PENNSYLVANIA.

GREASE-CUP.

1,234,307.

Specification of Letters Patent. Patented July 24, 1917.

Application filed October 7, 1916. Serial No. 124,231.

To all whom it may concern:

Be it known that I, GEORGE DONGES, a citizen of the United States, residing at Philadelphia, in the county of Philadelphia 5 and State of Pennsylvania, have invented certain new and useful Improvements in Grease-Cups, of which the following is a specification.

My invention relates to improvements in 10 grease cups for lubricating purposes in which a piston is employed within a grease containing cylinder for forcing the grease from the cylinder and through the discharge opening in the cup to the part to be lubricated.

The object of my invention is to provide 15 a grease cup of novel, simple and efficient construction having the grease cylinder formed of glass to permit the quantity of grease within the cup to be seen without opening the cup. A further object of my invention is to provide: firstly, a novel means of forming a tight joint between the 20 bottom of the cylinder and the body of the cup; secondly, a novel means for holding the cap or cover for the cup in place; and, thirdly, a novel packing for the piston which shall cause a close contact of the 25 piston with the necessarily irregular inner surface of the glass cylinder. To these ends the invention consists in the novel construction and combinations of parts herein-after fully described and claimed.

In the accompanying drawings, illustrating 30 my invention:

Figure 1 is a side view of a grease cup embodying my invention.

Fig. 2 is a vertical section thereof, on line 2-2 of Fig. 1.

Fig. 3 is a horizontal section, on line 3-3 of Fig. 1.

Fig. 4 is a horizontal section of the piston, on line 4-4 of Fig. 5.

Fig. 5 is a vertical section through the 45 piston.

Referring to the drawings, 5 designates a cylindrical casing open at its top and having a bottom wall 6 provided with a downwardly-extending, screw-threaded nipple 7 50 adapted to be screwed into the part to be lubricated, the nipple 7 having a grease discharge opening 8 extending therethrough. The sides of the casing 5 have large openings 9 therein through which may be seen 55 a glass cylinder 10 which is located within the casing.

The glass cylinder 10 is adapted to receive and contain the grease, and it rests upon a suitable packing ring 11 which is interposed between the lower end of the cylinder 10 60 and the bottom wall 6 of the casing 5. The cylinder 10 is forced down upon the packing ring 11 by a coiled spring 12 located within the upper portion of the casing 5 and interposed between a cap or cover 13 65 for the casing.

The cap 13 has a downwardly-extending flange 14 which surrounds and is fitted to the casing 5 and which is provided on opposite sides thereof with slots 15. These slots 70 15 extend upwardly from the bottom of the flange 14 and then incline in opposite directions to each other, as shown, and are adapted to receive pins 16 which project fixedly from the casing 5. The pins 16 rest 75 normally in depressed sockets 17 in the flange 14 at the upper or inner ends of the slots 15, and the parts of the flange 14 forming the sockets 17 are forced upwardly 80 against the pins 16 by the action of the spring 12, thereby holding the cap 13 in place and preventing accidental turning thereof.

When it is desired to remove the cap 13, it is turned by hand in the direction of the arrow, thereby freeing the sockets 17 from the pins 16, by forcing the cap 13 down a slight distance against the action of the spring 12. The further turning of the cap 13 in the direction of the arrow brings the 85 vertical portions of the slots 15 into alignment with the pins 16, whereupon the cap 13 may be moved upwardly from the casing 5, for the purpose of filling the cylinder 10 90 with grease and for other purposes. A reversal of the operation just described re-applies the cap 13 to the casing 5.

Within the cylinder 5 is a piston 18 having a rod or stem 19 which extends upwardly therefrom and into a hollow, cylindrical head 20 which is closed at its upper end and which is exteriorly screw-threaded and screwed into and through the cap 13 in a manner to be vertically adjustable 100 therein by turning the head 20. Encircling 105 the rod 19 is a coiled spring 21 which extends from the top of the piston 18 up through the hollow head 20 to the top thereof, and which is adapted to force the piston down upon the grease within the cylinder 10 to cause the proper feeding of the 110 grease through the discharge opening 8 to

- the part to be lubricated. By adjusting the head 20 the pressure of the spring 21 against the piston 18 may be nicely regulated. The upper end of the stem 19 has a head 22 of 5 a diameter slightly less than the interior diameter of the spring whose exterior diameter is slightly less than the interior diameter of the head 20. Thus the piston 18 is guided and prevented from tilting.
- 10 As the interior walls of glass cylinders are neither uniform in diameter nor perfectly round and free from other irregularities, I provide the piston 18 with an expandable and contractible packing ring 23 and 15 construct it as follows: On the lower end of the rod 19 are two disks or plates 24 and 25, the lower one 24 of which is screwed onto the lower end of the rod 19, and the upper one 25 of which is located between the lower 20 plate 24 and a flange or collar 26 on the stem 19. The packing ring 23 is located between the plates 24 and 25 and it is adapted to be clamped thereby and it comprises split annular sections 27, preferably formed 25 of leather and placed one upon the other so that the split portion 28 of one section will be lapped by the body portion of another section, as shown in Fig. 4, thus providing a tight joint between the cylinder 10 and 30 the piston 18, and permitting the entire ring 23 to expand and contract. Within the packing ring 23 is a split, annular spring ring 29 which operates to force all parts of the ring 18 outwardly against the inner wall of 35 the glass cylinder 10 and causes the ring 23 to engage the wall of the cylinder 10 with the proper degree of pressure at all times during the vertical movement of the piston, irrespective of any irregularities in the inner 40 wall of the glass cylinder. By turning the stem 19 within the lower plate 24, the distance between the plates 24 and 25 may be increased slightly, thereby lessening the pressure of the plates 24 and 25 against the 45 packing ring 18 and permitting the spring 29 to force the ring 23 out against the cylinder 10 with greater pressure. Thus the pressure of the packing ring 23 may be regulated by adjusting the plates 24 and 25.
- 50 I claim:
1. In a grease cup, a casing having a discharge opening in the bottom thereof and having a window in the side thereof, a glass cylinder within said casing and visible 55 through the window, packing between the lower end of the cylinder and the casing, a removable cap on the upper end of the casing, means to hold the cap in place upon the casing, and yielding means interposed between the top of the cylinder and the cap 60 and pressing the cylinder against the packing.
2. In a grease cup, a casing having a discharge opening in the bottom thereof and having a window in the side thereof, a glass cylinder within said casing and visible 65 through the window, packing between the lower end of the cylinder and the casing, a removable cap on the upper end of the casing, the casing and the cap having coöperating parts holding the cap in place on the casing, and yielding means interposed between the upper end of the cylinder and the cap 70 and pressing said coöperating parts together and pressing the cylinder against the packing. 75
3. In a grease cup, a casing having a discharge opening in the bottom thereof and having a window in the side thereof, a glass cylinder within said casing and visible 80 through the window, packing between the lower end of the cylinder and the casing, a removable cap on the upper end of the casing, the casing having a pin projecting therefrom, the cap having a slot formed therein 85 receiving the pin and the slot having an inclined portion adapted to engage the pin and move the cap toward the lower end of the cylinder when the cap is turned, and yielding means interposed between the cylinder 90 and the cap and adapted to force the cap up and the cylinder down.
4. In a grease cup, a casing having a discharge opening in the bottom thereof and having a window in the side thereof, a glass cylinder within said casing and visible 95 through the window, packing between the lower end of the cylinder and the casing, a removable cap on the upper end of the casing, the casing having a pin projecting therefrom, the cap having a slot formed therein 100 receiving the pin and the slot having an inclined portion terminating at its upper end in a depressed socket, the inclined portion of the slot being adapted to engage the pin and move the cap toward the lower end of the cylinder and the socket being thereafter adapted to receive the pin when the cap is turned, and yielding means interposed between the cylinder and the cap and 105 adapted to force the cap up and the cylinder down. 110

In testimony whereof I affix my signature hereto.

GEORGE DONGES.
